UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

RUFFLING MECHANISM FOR SEWING-MACHINES.

1,328,885.

Specification of Letters Patent.

Patented Jan. 27, 1920.

Application filed December 2, 1916. Serial No. 134,658.

To all whom it may concern:

Be it known that I, JAMES R. MOFFATT, a citizen of the United States, residing at Chicago, in the county of Cook, State of Illinois, have invented certain new and useful Improvements in Ruffling Mechanism for Sewing-Machines, of which the following is a description, reference being had to the accompanying drawing and to the figures of reference marked thereon.

The invention relates to new and useful improvements in ruffling mechanisms for sewing machines, and more particularly to a ruffling mechanism which is supported above the work support and operated by the needle bar of the sewing machine.

An object of the invention is to provide a ruffling mechanism of the above character wherein the ruffling device will be bodily raised with the presser foot when said foot is raised for the insertion of the material underneath the same.

In the drawings, which show by way of illustration one embodiment of the invention:

Figure 1 is a front view of a sewing machine embodying the improvements, parts being broken away to show the looper cooperating with the needles beneath the work support;

Fig. 2 is an end view of the machine;

Fig. 3 is an enlarged view showing the relative position of the ruffling blade to the presser foot when said ruffling blade is at the forward end of its stroke;

Fig. 4 is a similar view, but showing the ruffling blade retracted;

Fig. 5 is a detail in section, showing the operating sleeve for moving the ruffling blade back and forth;

Fig. 6 is a detail showing the presser foot, the work support, the needles and the manner of feeding the fabric to be stitched to the needles in one use of my invention;

Fig. 7 is a view showing diagrammatically the manner of stitching the sections of fabric together;

Fig. 8 is a view showing, more or less diagrammatically, a section of a lady's vest in which the pocket has been stitched by my improved mechanism; and

Fig. 9 is a plan view showing the supporting block and bracket at the upper end of the presser bar.

The improved ruffling mechanism is par-

ticularly adapted for stitching two sections of fabric together and the gathering of one of the sections relative to the other as it is being stitched. This is accomplished by my improved ruffling mechanism which is located above the work support. The ruffling blade is carried by a supporting member which extends vertically and is pivoted at its upper end to a bracket rigid with the presser bar so that the up and down movements of the presser bar will be imparted to the ruffling blade support. The ruffling blade support is moved back and forth from a connection with the needle bar. The ruffling blade is a two-motion blade having back and forth movements only, and said blade is pivotally carried by its support. A spring presses the blade toward the work support, and a finger carried by the blade holder engages the presser foot so that when the presser foot is lifted, the blade will be lifted therewith. The bracket supporting the ruffling blade is carried by the presser bar and, therefore, when the presser bar is lifted for the insertion of the material underneath the same, not only the ruffling blade is raised with the presser foot, but the supporting members for the ruffling blade are also raised, giving ample space underneath the same for manipulation of the material.

Referring more in detail to the drawings:

I have shown my improved ruffling mechanism applied to a sewing machine having a supporting bed 1, a work support 2, and an overhanging arm 3 on which is mounted a needle lever 4. The needle lever is oscillated by a pitman 5 from an eccentric on the main shaft 6. At the front end of the overhanging arm there is a needle bar 7 which carries two needles 8 and 9. Coöperating with the needles above the work support is a cross thread laying mechanism which includes a fixed thread guide 10 and a movable thread hook 11. Said thread hook is oscillated so as to engage the cross thread and form a loop therein for the needle farthest from the thread guide to enter, and thus the cross thread is laid back and forth so as to join the needle threads on the upper surface of the material being stitched.

Coöperating with both of the needles 8 and 9 is a looper 12 which is mounted on a

suitable looper carrier 18, and this looper carrier is moved back and forth by a link 14 which is pivoted to the needle lever extension 15. This looper causes a looper 5 thread to be concatenated with both of the needle loops, and thus the needle threads are joined on the lower face of the fabrics being stitched.

The material is held on the work support by 10 a presser foot 16 which is carried by a presser bar 17. The presser bar 17 is connected by an arm 18 to a guide bar 19 which is movable in suitable bearings in the overhanging arm, and this guide bar with the connecting 15 arm prevents the presser bar from turning in its bearings. The presser bar may be raised by a hand lever 20 which engages a pin 21 carried by the presser bar. The presser bar may also be raised by a lever 22 20 which engages a pin 23 carried by the presser bar. This lever 22 may be connected to a suitable knee shift or treadle.

The presser foot 16 has an up-turned toe 24 and an edge guiding section 25 which extends in front of said up-turned toe. My improved ruffling mechanism consists of a ruffling blade 26 which is clamped to a ruffling blade holder 27 by means of a screw 28. The ruffling blade holder 27 is mounted 30 on a ruffling blade support 29. Said holder is pivoted at 30 to the support, and a spring 31 surrounding the pivot bolt is connected at one end to the holder, while the other end of this spring is fixed to the support 29 and 35 the spring normally tends to turn the ruffling blade toward the work support. The downward movement of the ruffling blade through the action of the spring 31 is limited by a finger 32 which is rigidly attached to the ruffling blade holder 27 and bears on the upper face of the presser foot 16. Said finger slides back and forth on the presser foot. This finger is so positioned as to maintain the points of the 40 ruffling blade substantially on a line with the plane of the lower surface of the presser foot so that, as the ruffling blade moves back and forth, it will engage the upper face of the fabric directly beneath the blade and 45 will gather the same. The fabric is fed through the machine by a feed dog 33 and the ruffling blade is timed so as to move slightly faster or to have a greater feed 50 stroke than the feed dog, and this gathers the material.

The support 29 for the ruffling blade consists of a bar 34 to the lower end of which is attached a bracket 35. A ruffling blade 60 is pivoted to this bracket. The bracket is adjustably connected to the bar 34 and is held in adjusted position by a screw indicated at 36. This screw passes through a slot 37 in the bracket, and the bracket has a rib 38 formed thereon which engages a 65 groove in the head at the lower end of the

bar 34. This structure in detail forms no part of the present invention and will not be further described.

The rod 34 is pivoted at 39 to a depending arm 40 of a bracket 41 which is rigidly connected to the presser bar 17. On the upper end of the presser bar there is a block 42 which is secured to the presser bar in any suitable way. The bracket 41 is pivotally connected to this block. Said bracket has 70 a slot 43 formed thereon which engages the pin 21 and a screw 44 passing through the slot clamps the bracket in an adjusted position on the block 42. This slot 43 is substantially horizontal and permits of the 75 bracket being adjusted back and forth in a horizontal plane. The pin 44 is threaded into the block 42 and has an enlarged head overlapping the side edges of the slot. Rigidly attached to the needle bar 7 is an arm 80 45. A sleeve 46 is pivotally connected to the arm 45 by means of a suitable pivot pin 47. The sleeve 46 engages the bar 34. This arm 45 extends rearwardly from the needle bar 7 and its rear end 48 is forked so as to slid- 85 90 ingly engage the presser bar. The purpose of this extension is to prevent the arm from turning on the needle bar. The arm is clamped to the needle bar by a set-screw 49 and also by a clamping screw 50. The arm 95 is split, and this screw 50 drawing the sections of the arm together firmly clamps it to the needle bar. The rear end of the arm, however, as above noted, freely slides on the 100 presser bar.

As the needle bar reciprocates, the sleeve 46 will slide up and down on the bar 34. When the bracket 41 is adjusted so that the pivot point 39 between the rod 34 and the bracket is in front or to the right of the 105 pivot point 47, as viewed in Fig. 2, then an up and down movement of the sleeve will cause the bar 34 to be oscillated on said pivot support 39. The extent of oscillation will depend upon the distance at which this 110 pivot point 39 is set in advance of the pivot point 47. This distance may be adjusted or varied by shifting the bracket 41 on the presser bar. When it is desired to adjust the bracket the screw 44 is loosened and the 115 bracket may be readily moved forwardly or rearwardly, as desired. When it is moved forwardly or to the right, as viewed in Fig. 2, the stroke of the ruffling blade will be increased and when moved to the left, as 120 viewed in this figure, then the stroke of the ruffling blade will be decreased. When this bracket is moved for increasing the stroke of the ruffling blade, the vibrating position of the ruffling blade will be changed. In 125 other words, if the pivot pin 39 is moved to the right, as viewed in Fig. 2, the ruffling blade will be moved farther to the left when the needle bar is moved upwardly. The position of the ruffling blade may be readily 130

varied on the bar 34 by loosening the screw 36 and shifting the bracket 35 relative to the bar 34. This enables the ruffling blade to be properly set relative to the presser foot so as to feed the material which is gathered up to a point where the feed of the machine will readily carry the same underneath the presser foot.

While my machine may be capable of various uses, it is especially designed for the stitching of pockets in ladies' vests. In Fig. 8 of the drawings, I have shown, more or less diagrammatically, a section of a lady's vest the body of which is indicated at 51. This vest is formed with a slit extending vertically thereof, and the opening thus formed is covered by the pocket 52. The pocket is slightly larger than the length of the slit and, therefore, the edges of the pocket must be gathered in order that the pocket may be smoothly stitched to the garment. In the stitching of a pocket of this character, the body of the garment which is indicated at 51 in Figs. 6 and 7 is fed to the stitching mechanism so that the needle 9 enters the body portion of the garment while the needle 8 passes outside the edge thereof. Thus the looper thread covers the under edge of the garment. The pocket is fed to the needles so that its edge passes between the needles and this edge is guided by the edge guiding member 25. The ruffling blade engaging the pocket 52 will gather the edge thereof as it is fed under the presser foot and this edge of the pocket will be covered by the cross thread and thus the pocket will be stitched to the garment.

In Fig. 7 of the drawings, the looper thread is indicated at *l*, the needle thread for the needle 8 at *n*, the needle thread for the needle 9 at *n'*, and the cross thread at *c*. When the presser foot is raised to place the section of fabric underneath the same, the finger 32 engaging the presser foot will limit the swinging movement of the ruffling blade 27 about the pivotal support 30 therefor and will thus keep the points of the ruffling blade well above the upper face of the work support which enables the operator to manipulate the fabric back and forth until it is properly positioned for beginning the stitching operation. Then again when the presser foot is raised the support for the ruffling blade is also raised therewith and

this gives ample space underneath the supporting members for the ruffling blade for the manipulation of the material when placing the same beneath the presser foot.

It is obvious that minor changes in the details of construction and the arrangement of parts may be made without departing from the spirit of the invention, as set forth in the appended claims.

Having thus described the invention, what is claimed as new is:—

1. The combination of a stitch forming mechanism including a needle bar, a needle supported thereby, means for reciprocating the needle bar, a presser foot, a presser bar carrying said presser foot, a ruffling mechanism including a ruffling blade, a support on which said ruffling blade is pivotally mounted, means for yieldingly forcing said ruffling blade downwardly, means for oscillating said support, a bracket fixedly connected to the presser bar and pivotally supporting the upper end of said ruffling blade support, means for raising the presser bar and the bracket connected thereto, and means for limiting the downward movement of the ruffling blade when said presser bar and bracket are lifted.

2. The combination with stitch forming mechanism including a needle bar, a needle supported thereby, means for reciprocating the needle bar, a presser foot, a presser bar carrying said presser foot, of a ruffling mechanism including a ruffling blade, a support on which said ruffling blade is pivotally mounted, means for yieldingly forcing the ruffling blade downwardly, means for limiting the downward movement of the ruffling blade, means for oscillating said support, a member fixed to the upper end of the presser bar, a bracket pivotally supporting the upper end of the ruffling blade support, means for connecting the bracket to said member whereby said bracket may be adjusted horizontally for varying the stroke of the ruffling blade, and means for raising the presser bar.

In testimony whereof, I affix my signature, in the presence of two witnesses.

JAMES R. MOFFATT.
